(57) **CLAIM**

The ornamental design for a foldable stand for a mobile device, as shown and described.

DESCRIPTION

FIG. 1 is a top view of the exterior of a foldable stand for a mobile device showing the claimed design in a folded position;

FIG. 2 is a bottom view thereof;

FIG. 3 is a front view of the thereof;

FIG. 4 is a rear view thereof;

FIG. 5 is a right side view thereof;

FIG. 6 is a left side view thereof;

FIG. 7 is a top view of the exterior thereof in which the foldable stand for a mobile device is in a completely unfolded position;

FIG. 8 is a bottom view of the interior thereof;

FIG. 9 is an end view thereof;

FIG. 10 is an opposite end view thereof;

FIG. 11 is a left side view thereof;

FIG. 12 is a perspective side view thereof in which the foldable stand for a mobile device is in a first partially folded position; and,

FIG. 13 is a left side elevational view thereof.

The regularly broken lines in FIGS. 7-13 show portions of the foldable stand that form no part of the claimed design. The broken lines that include two relatively shorter dashes followed by a relatively longer dash show environmental subject matter only and form no part of the claimed design.
